DESIGN FOR A GAUGE HANDLE

Robert E. Snyder, Pasadena, Calif.

Application August 23, 1944, Serial No. 114,982

Term of patent 14 years

(Cl. D52—1)

To all whom it may concern:

Be it known that I, Robert E. Snyder, a citizen of the United States of America, residing in the city of Pasadena, in the county of Los Angeles, State of California, have invented a new, original, and ornamental Design for a Gauge Handle, of which the following is a specification, reference being had to the accompanying drawing forming a part thereof.

Fig. 1 is a perspective view of a gauge handle showing my new design,

Fig. 2 is an elevational view of the same, and

Figs. 3 and 4 are opposite end views of the handle.

I claim:

The ornamental design for a gauge handle, substantially as shown.

ROBERT E. SNYDER.
